UNITED STATES PATENT OFFICE.

CHARLES L. COLE, OF BUSHNELL, ILLINOIS, ASSIGNOR OF ONE-HALF TO
WILLIAM A. STINE, OF PEORIA, ILLINOIS.

CLOTHES-POUNDER.

SPECIFICATION forming part of Letters Patent No. 653,641, dated July 10, 1900.

Application filed June 6, 1898. Serial No. 682,678. (No model.)

To all whom it may concern:

Be it known that I, CHARLES L. COLE, a citizen of the United States, residing at Bushnell, in the county of McDonough and State 5 of Illinois, have invented certain new and useful Improvements in Clothes-Pounders; and I do hereby declare that the following is a full, clear, and exact description of the invention, which will enable others skilled in 10 the art to which it appertains to make and use the same.

My invention relates to certain new and useful improvements in atmospheric clothes washers or pounders, by means of which a 15 washer is provided that is well adapted for the purpose designed.

My invention consists, essentially, in the provision of a truncated conical body or shell having located at a suitable point therein a 20 horizontally-arranged diaphragm provided with suitable perforations, through which water and air are permitted to pass, of a compartment carried in conjunction with the diaphragm and resting on the same and having 25 suitable inwardly-projecting plates and also having perforations suitably located in the walls of said compartment, and of a tubular extension extending up therefrom and having 30 suitable inwardly-projecting plates alternating from opposite sides therein, in combination with a centrally-disposed cylinder having horizontally-arranged inwardly-projecting plates one above the other and extending from opposite sides, and of an air-tight compartment and air-vents in the 35 extreme upper portion of said cone, suitable tubes extending from the upper end of the centrally-disposed cylinder to a point below the same and opening into a compartment 40 formed by the diaphragm and air-tight compartment.

A further object of my invention is to provide in connection with the shell having the perforated diaphragm the partitioned compartment with the tubular extension therefrom, the air-tight compartment and the centrally-disposed cylinder with inwardly-projecting plates and the tubes and air-vents in the upper end thereof, a hollow wedge-shaped 45 extension extending from the diaphragm to

a point near the bottom of the shell and having suitable perforations arranged at intervals in the base thereof, in combination with a partition extending in like manner from the diaphragm and in a plane at right angles 55 to the wedge-shaped extension. This arrangement of parts and the manner of carrying the same serves as a brace for the shell as well as prevents a too intimate contact of the clothes with the diaphragm, at the same 60 time allowing the ingress and egress of the water and air into and out of the compartments above.

That my invention may be more fully understood, reference is had to the accompanying 65 drawings, in which—

Figure 1 is a vertical section of my improved washer. Fig. 2 is an elevation of the same. Fig. 3 is a bottom plan of Fig. 2. Fig. 4 is a horizontal section taken on the line Y Y of 70 Fig. 1. Fig. 5 is a horizontal section taken on the line X X of Fig. 1. Fig. 6 is a perspective view of the wedge-shaped extension or partition. Fig. 7 is a perspective view showing the diaphragm, the compartment 75 carried in conjunction therewith and resting thereon, and the wedge-shaped extension and partition depending therefrom.

In the drawings like letters of reference indicate the several corresponding parts, as illustrated in the figures.

A is a cone made of suitable material, such as tin or the like, provided with the upper small tubular projection a, and removably carried therein is a handle a', having a ferrule a² on its lower extremity and in the tube, and a³ is a fastening device adapted for retaining the ferrule and handle in the tube a. At a point just below the tubular projection a and upon the conical part of the washer I 90 have shown a series of rows of perforations a⁴, provided as air-vents therefor.

Describing the lower half of the machine, B is a diaphragm (best shown in Figs. 7 and 1) fitting snugly the inner wall of the cone 95 at a point shown in Fig. 1, and B' is a wedge-shaped extension and water-inlet pocket extending from the diaphragm down to a point near the bottom of the cone and is provided with the converging sides b b and the bottom 100

b' and with the openings *b*² arranged at intervals therein, which may be of the shape shown and in a line or in any way most suitable to attain a perfect operation. While I have shown but one of these pockets, I do not wish to limit myself to one, for one or more may be provided, as is desired.

C is a partition carried at right angles to the extension *B'* and extending also from the diaphragm *B* down to a point near the bottom and in a plane at right angles with the bottom of the extension *B'*, both of which have a bearing relation in conjunction with the face of the cone against the articles to be washed. This manner of combining the several parts referred to divides the lower half of the washer into the compartments *K*.

D is a compartment carried in conjunction with the diaphragm *B*, which forms the lower wall thereof and is adapted to be carried on the upper face thereof and parallel with the wedge-shaped extension or water-inlet pocket *B'*. This compartment is provided with inwardly-projecting plates *d*², and the upper and lower walls of the compartment are provided with perforations, as shown at *e e'*.

E is a tubular extension extending up from the compartment *D* and provided with the oppositely - arranged inwardly - projecting plates *e*² *e*², extending from the inner wall of the tube to a point just beyond the center. I have shown extending from a point just below the air-vents *a*⁴ to a point just above the diaphragm *B* on the inner wall of the cone a series of tubes *F*, arranged at intervals around the circumference thereof, the bottom of which said tubes have inwardly-turned elbows *f*, and suitably carried from a point beginning with the top of these tubes *F* is shown a cylinder *G*, similar to the tubular extension *E*, and which said cylinder extends down to a point just below the top of the tubular extension *E* and is large enough in diameter to permit the tubular extension *E* to extend into the cylinder *G* a short distance, as shown. This cylinder is provided with a series of oppositely-arranged inwardly-projecting plates *g* from the inner wall of the cylinder to a point just beyond the center thereof.

H is a diaphragm carried substantially as shown in Fig. 1, and adapted to serve as the top partition of the compartment *I*, formed by the lower partition or diaphragm *B*. This diaphragm *H* also forms the lower partition for an air-tight compartment *I'*, formed by the upper diaphragm *J* surrounding the cylinder *G* at a point near its upper extremity and in the manner shown.

By examining Fig. 1 it will be seen by the arrows provided the direction in which the water and air take their course. When the washer is being used, sufficient space being provided to allow for an easy passage of the water when the device is forced into the water, the action of the partitions and air upon the water causing the same to be agitated

sufficiently to stir up the suds and to thoroughly cleanse the articles subjected to this operation.

The construction of the washer is such that it is very light, and the manner of securing the handle gives an opportunity of releasing the same at any time, the arrangement or construction of the compartment, tubes, and inwardly-projecting plates being such as to prevent any water escaping through the air-vents in the upper portion of the same.

In describing the water-inlet pocket *B'*, the compartment immediately above, with its inwardly-projecting plates, and the tube and cylinder, with the air-chamber and the tubes carried on the inner wall of the cone, I do not wish to limit myself to the exact construction, the number of tubes, or the number of inlet and outlet openings, nor to the number of inwardly-projecting plates shown in the compartment, tube, and cylinder for checking the water as it forces its way up into the cone, as numerous changes may be made without departing from the original idea herein illustrated.

The division of the shell by the diaphragm *B* at the point shown in the figures permits the same to be immersed a sufficient depth before the diaphragm contacts with the clothes, compartments being formed by the provision of the partition *C* and the wedge-pocket *B'*, having converging walls, as shown, and suitable openings whereby the water is permitted to pass up through the pocket and through the openings provided in the diaphragm into the chamber *D*, which has suitable plates, as shown, around which the water must pass to get into the upper compartment *I*, the construction of this passage being such as to agitate the same, and while it is possible for some to pass up through the pipes *F* the greatest quantity of water will be forced up into the cylinder or tubular passages *E* and *G*, which also have plates, but which overlap each other, causing a further agitation of the water, the air being forced out through the vents *a*⁴, and when the shell is withdrawn the water reverses its movements and drops out of the shell.

Having thus fully described my invention; what I claim, and desire to secure by Letters Patent of the United States, is—

1. In a clothes-pounder, the combination of an outer shell, a diaphragm engaging the inner wall of said shell, a wedge-shaped pocket depending from the diaphragm provided with a series of perforations in the bottom thereof, a partition carried at right angles to said pocket, the diaphragm, pocket and partition providing suitable compartments between them, of a vertically-arranged cylinder centrally disposed in said shell and above the diaphragm, said shell being provided with suitable air-vents in the upper end thereof, all substantially as and for the purpose set forth.

2. In an atmospheric washer or pounder,

- the combination with the truncated conical body, a diaphragm dividing said washer into distinct compartments, of a centrally-disposed cylinder or tubular passage arranged 15
5 in the upper portion of said washer and surrounded by an air-tight compartment, said cylinder or tubular passage being provided with inwardly-projecting plates from opposite sides, all arranged substantially in the 10 manner and for the purpose described.
3. In a clothes-pounder, a conical shell, provided with a diaphragm dividing said shell, a compartment covering suitable perforations in said diaphragm and having extending up 20
therefrom a cylindrical body with alternately-arranged plates overlapping each other from opposite sides, in combination with a pocket carried beneath the diaphragm and having converging sides, and of inlet-openings suitably arranged for the ingress and egress of water therein, all substantially as described and shown.

In testimony whereof I affix my signature in presence of two witnesses.

CHARLES L. COLE.
